UNITED STATES PATENT OFFICE.

EUGENE SONNTAG, OF NEW YORK, N. Y.

WINDOW-SCREEN.

1,136,730.

Specification of Letters Patent. Patented Apr. 20, 1915.

Application filed April 21, 1914. Serial No. 833,439.

To all whom it may concern:

Be it known that I, EUGENE SONNTAG, a citizen of the United States, and a resident of the city of New York, Long Island City, 5 borough of Queens, in the county of Queens and State of New York, have invented a new and Improved Window-Screen, of which the following is a full, clear, and exact description.

10 This invention relates to window screens of that type including two sections arranged respectively at the top and bottom of the window frame to close the gaps at the top and bottom of the lower sash when the latter 15 is raised for ventilating purposes, the said sections of the screen being mounted on runners so as to be sliding, and having clamps for engaging the runners, whereby the screen sections can be held in place and readily adjusted.

20 The invention has for its general objects to improve and simplify the construction of window screens of the character referred to so as to be reliable and efficient in use, readily adjusted to open or closed position, and so designed as to absolutely prevent the entrance of flies, mosquitos or other insects, as cracks between the frames of the screens and the window frame and sashes are avoided.

30 Another object of the invention is the provision of a window screen frame which is manufactured in corner or end sections which can be adjustably connected together to form a rectangular frame of any desired 35 width or size, according to the dimensions of the window to which the frame is to be applied, and after the sections are nailed or otherwise secured together, the netting is fitted and fastened to the resultant frame so 40 as to make a non-alterable fixed frame which is detachably and slidably mounted in the window.

45 A further object of the invention is the provision of a window screen frame of the character referred to with novel means for detachably connecting the frame with runners arranged on the frame of the window, such means serving as clamps whereby the screen can be locked in raised or lowered position on the runners.

50 Still another object of the invention is to provide a screen frame having a novel arrangement of sealing strips whereby the point of contact of the screen frame with the window frame or sash is effectively

sealed so that insects cannot enter through the cracks that would otherwise be formed.

With such objects in view, and others which will appear as the description proceeds, the invention comprises various novel 60 features of construction and arrangement of parts which will be set forth with particularity in the following description and claims appended hereto.

65 In the accompanying drawing, which illustrates one embodiment of the invention, and wherein similar characters of reference indicate corresponding parts in all the views, Figure 1 is a vertical section of the window frame, showing the lower sash open 70 and the upper and lower screens in position; Fig. 2 is a perspective view of the sections of the upper screen before the said sections are fastened together to form a fixed screen frame; Fig. 3 is a perspective view of two 75 corner sections of the lower screen frame; Fig. 4 is a fragmentary front view of the lower screen; Figs. 5 and 6 are enlarged sectional views respectively on the lines 5—5, 6—6, Fig. 4; and Fig. 7 is a perspective view 80 of one corner of a screen frame, showing the runner-engaging clamp detached from its bolt.

85 Referring to the drawing, A designates an ordinary window frame having the upper and lower sashes 1 and 2, the upper sash being slightly lowered and the lower sash being raised about three-quarters its range of movement. The gap above the lower sash is closed by an upper screen B, and the gap 90 below the lower sash is closed by a lower screen C, the screens together being in vertical dimensions about equal to the total length of movement of which the lower sash is capable, whereby the bottom of the 95 upper screen will overlap the top bar 3 of the lower sash, and the top of the lower screen will overlap the bottom bar 4 of the lower sash. The frame A has longitudinal 100 runners 6 on which the upper and lower screens are fastened and on which they are capable of having a vertical sliding movement. The runners are rabbeted to provide a longitudinal flange 7 behind which flanges on the side bars of the screen frames engage. 105

The upper screen has its frame made in two sections b and b', and each section comprises a vertical bar 8 and horizontal bars 9 and 10 which are connected by miter or other joints 11, and in the joints are inserts 110

12 for reinforcing and stiffening purposes. The bar 9 has a longitudinal slot 13 extending inwardly from its free end to a considerable distance, and the bar 10 has a tongue 14 extending longitudinally from its free end and is of considerable length. The sections *b* and *b'* are fitted together in such a manner that the tongue 14 on one section will enter the slot 13 in the corresponding portion of the other section, whereby the two sections adjustably interfit, so that the frame can be lengthened or contracted to fit any size window frame. After the sections have been fitted together to produce a frame of proper length, the bar 10 of each section is nailed to the bar 9 of the other section. The netting 15 is then secured to the frame in any desired manner. According to the present method the front surfaces of the bars 8, 9 and 10 of the screen frame are provided with longitudinal grooves 16, and strips 17 are fastened to the bars of the frame, and these strips have tongues 18 to enter the grooves 16 and thereby clamp the edges of the netting to the frame. As shown in Fig. 1, the top bar of the upper screen is provided with a flexible sealing strip of rubber, felt or any other suitable material, and this strip 19 is inserted between the netting-holding strip 17 and the top bar of the screen frame, and this sealing strip 19 is adapted to bear against the top of the window frame and close the crack that would otherwise be formed. A sealing strip 20 is applied to the bottom of the screen frame so as to engage the upper bar 3 of the lower sash and close the crack. This sealing strip 20 is fastened to the screen frame in any suitable manner, as, for instance, by a stiff strip 21 of wood or other suitable material which is nailed to the screen frame.

The vertical bars 8 have their outer edges rabbeted to form flanges 22 which engage behind the flanges 7 of the runners 6, so that the screen can be slid up and down on the runners. A clamping block 23 is provided at each corner of the screen frame and projects outwardly to engage over the front of the runners 6 and engage the flange 7 thereof. These blocks are set into recesses 24 provided in the corners of the screen frame, and are held in place by bolts 25 that pass through the screen frame and through the clamping blocks 23, the bolts having thumb nuts 26 for easy manipulation. As shown in Fig. 7, each block 23 has a rib 27 to engage in the groove 16 of the bar 8 to which the clamping block is fastened, and the recess for each clamping block is provided between the end of the vertical screen-holding strip 18 and the bottom edge of the adjacent horizontal screen-holding strip 18, as clearly shown in Fig. 7. Normally the blocks 23 are clamped tightly in engagement with the

runners by the nuts of the bolts being jammed tight, but when the screens are to be slid up and down the nuts are loosened so as to release the clamping blocks 23 from the runners to allow free movement. By detaching the clamping blocks the screen can be wholly removed from the window frame, as at the end of the season, or when the windows are to be cleaned.

The lower screen C is constructed in details on the same principles as the upper screen B, except that the frame of the lower screen is made of angular or corner sections *c*, there being four in number so that the screen frame can be made of any desired height or width, according to the size of the window frame, and as the sections of the lower screen frame are made of similar stock as the upper screen frame, the parts are correspondingly numbered by reference characters, so that a repeated description is unnecessary.

From the foregoing description taken in connection with the accompanying drawing, the advantages of the construction and method of operation will be readily understood by those skilled in the art to which the invention appertains, and while I have described the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. A window screen composed of sections formed of bars, each pair of corresponding bars of the sections having respectively a longitudinal slot and a tongue fitting in the slot, whereby a frame of any desired size may be formed, a single piece of netting having its four edges fastened to the frame, and strips fastening the netting to the frame and serving to cover the gaps between the slotted and tongued bars of the sections.

2. A window screen composed of sections formed of bars, each pair of corresponding bars of the sections having respectively a longitudinal slot and a tongue fitting in the slot, whereby a frame of any desired size may be formed, a netting for the frame, strips fastening the netting to the frame and serving to cover the gaps between the slotted and tongued bars of the sections, a flexible sealing strip extending horizontally from one of the horizontal bars of the frame, and a flexible sealing strip extending vertically from the other horizontal bar of the frame.

3. A screen comprising a frame having runner-engaging flanges at its ends, a plurality of runner-engaging blocks at the ends co-operating with the said flanges to mount

the screen in a window frame, and means for loosening or tightening the blocks, whereby the blocks can be held in sliding or frictional engagement with the runners, in combination with a window frame, and runners on opposite sides of the window frame and each provided with a screen-guiding flange, said screen frame being disposed between the runners, with the flanges of the screen frame 10 engaging the flanges of the runners and the blocks projecting beyond the screen frame and engaging the flanges of the runners.

4. A screen comprising a frame having grooved vertical and horizontal bars, a netting 15 covering the frame, the vertical bars of the frame having runner-engaging flanges, tongued strips secured to the bars of the frame and serving to fasten the netting thereto, the vertical strips being of less 20 length than the distance between the horizontal strips to provide recesses between the ends of the vertical strips and the horizontal strips, clamping blocks disposed in said recesses, and the said blocks having tongues 25 to engage in the grooves of the vertical bars, and the blocks extending outwardly from the sides of the bar to coöperate with the flanges on the vertical bars to engage screen runners, and means for fastening the blocks 30 to the vertical bar.

5. A screen composed of sections forming the frame, each section including a pair of rigidly connected members, one member having a longitudinal slot extending inwardly from one end, and the other member having 35 a longitudinal tongue adapted to enter the slot of the slotted member of another section, a netting fastened to the frame, strips fastened to the front side of the screen frame and bridging the gaps between the sections 40 thereof, and sealing strips at the top and bottom of the frame, one sealing strip extending upwardly and the other strip extending laterally from the frame.

6. A rigid rectangular screen frame including a plurality of sections, each section consisting of rigidly connected members each having on one side face a groove for receiving a piece of netting, one member having a longitudinal slot and the other having 45 a longitudinal tongue, in combination with a single piece of netting fastened at all its edges to the frame.

In testimony whereof I have signed my name to this specification in the presence of 50 two subscribing witnesses.

EUGENE SONNTAG.
